VENETIAN BLIND BOTTOM BAR
ORGANIZATION

Hans K. Lorentzen, Florham Park, N. J., assignor
to Lorentzen Hardware Mfg. Corp., New York,
N. Y., a corporation of New York

Application December 6, 1950, Serial No. 199,484

11 Claims. (Cl. 160—178)

1

This invention relates to Venetian blinds and, more particularly, to a Venetian blind bottom bar assembly and fittings therefor.

A Venetian blind is essentially an assembly of spaced, superimposed slats supported by two or more so-called "ladder tapes," each ladder tape consisting of a pair of spaced, vertical tapes connected at intervals by short, horizontal tapes called "rungs" which support the slats. A somewhat heavier, lowermost slat termed the "bottom bar" receives the lower ends of the ladder tapes.

Venetian blinds are customarily provided with two or more lift cords, the lift cords usually being passed downwardly through holes in the slats adjacent each ladder tape and anchored to the bottom bar. In raising the blind to open position, the lift cords are pulled upwardly so as to raise the bottom bar, the ladder tapes collapsing and the slats accumulating on the top of the bottom bar. It is sometimes desirable to remove some or all of the slats of the blind for cleaning or replacement and the slats cannot be withdrawn from the ladder tapes without first detaching the lift cords from the bottom bar and pulling the lift cords as in raising the blind to withdraw the cords from the slats.

In the form shown of the present invention, a bottom bar assembly is comprised of a sheet metal channel of generally rectangular cross section, the open side of which is closed by a cover which may be formed of a Venetian blind slat. The lower ends of each ladder tape and associated lift cord are received by a stamped sheet metal anchor located between the channel and the cover and having ladder-tape-engaging portions and a lift-cord-engaging portion of the so-called "keyhole slot" type which is adapted to receive the end of a lift cord to which an enlargement, such as a sheet metal bead, previously has been attached. The anchor is particularly adapted for easy insertion or withdrawal of the lift cord and is located beneath each lift cord opening or rout hole of the bottom bar cover, the anchor being slidable relative to the cover to uncover the large end of the keyhole slot for insertion or withdrawal of the cord and to uncover the smaller end of the slot for retention of the cord. In some respects, this assembly and fitting is an improvement over that shown in Harry Nelson application S. N. 780,653 and my prior application S. N. 142,492. This fitting and assembly has an improved appearance and firmly retains the lift cord; and, at the same time, the lift cord can

2

be easily detached or attached without disassembling the bottom bar.

An object of this invention is to provide an improved metal bottom bar assembly and fitting for Venetian blinds, in which the lift cord is securely anchored within the bottom bar, that may be quickly detached or attached without special tools and without disassembling the bottom bar, and which has an improved appearance.

Other objects of this invention are to provide such an assembly which may be easily and economically fabricated from rolled or stamped sheet metal parts, which is easily assembled, and which is durable and dependable in operation. Other objects, and objects relating to details and economies of manufacture, assembly, and use, will more definitely appear in the detailed description to follow.

My invention is clearly defined in the appended claims. In the claims, as well as in the description, parts are at times identified by specific names for clarity and convenience, but such nomenclature is to be understood as having the broadest meaning consistent with the context and with the concept of my invention as distinguished from the pertinent prior art. The best form in which I have contemplated applying my invention is illustrated in the accompanying drawings forming part of this specification, in which:

Fig. 1 is a perspective view of a lift cord and ladder tape anchor constructed in accordance with the present invention.

Fig. 2 is a perspective view of a bottom bar assembly, only a portion of the bottom bar, lift cord, and ladder tape being shown. The use of a screw driver to displace the anchor in order to release the lift cord is shown diagrammatically.

Fig. 3 is a view similar to Fig. 2, the lift cord anchor having been displaced and the lift cord disengaged from the bottom bar.

Fig. 4 is a top plan view of the assembly, only a portion of the bottom bar and ladder tape being shown. The lift cord has been omitted from this view.

Fig. 5 is a transverse section through the bottom bar assembly, including the lift cord and ladder tape, taken on the line 5—5 of Fig. 4.

Fig. 6 is a vertical section of the assembly taken on the line 6—6 of Fig. 5; the lift cord being shown engaged with the anchor.

Fig. 7 is a view similar to Fig. 6, the anchor having been displaced and the lift cord disengaged from the bottom bar.

Referring now to the drawings, the bottom

bar assembly, with which the lift cord and ladder tape anchor of the present invention is associated, is formed of a bottom bar channel 10 and a cover 11 closing the open side of the channel. The channel 10, which is of uniform cross section throughout its length, may have the cross section indicated in Fig. 5 in which a sheet metal strip has been formed into a channel of generally rectangular cross section having a generally flat bottom wall 12 and upwardly extending side walls 14, 14 terminating in inwardly directed longitudinal edges 15, 15. In the form of channel shown in Fig. 5, portions of the bottom wall 12 have been folded upwardly to form two parallel ribs 16, 16 extending upwardly from the bottom wall of the channel and terminating generally between the edges 15, 15 of the channel.

The cover 11 for the open side of the bottom bar channel is preferably formed of a resilient, transversely arched strip of metal such as metal Venetian blind slat stock. Holes 17 are provided for entrance of the lower ends of the lift cords into the bottom bar assembly. These holes may conveniently be formed on the same machine used for punching the lift cord holes in the metal slats of a Venetian blind.

The cover 11 is held in position on the channel 10 by the edges 15, 15 of the channel which overlie the edges of the cover. The cover may be inserted in the channel either by telescoping it with the channel or springing it into engagement by temporarily bending the channel to increase its transverse curvature. An end cap, not shown, is preferably used to close the ends of the bottom bar channel 10 so as to improve the appearance of the bottom bar.

A lift cord and ladder tape anchor 19 is located between the cover 11 and the ribs 16, 16 of the channel at each of the holes 17 in the cover for receiving the lift cords. This general organization is disclosed in Nelson application S. N. 780,653.

The anchor 19 of the present invention, which is in some respects an improvement over that shown in the Nelson application and my prior application S. N. 142,492, may be formed of a generally rectangular sheet metal stamping adapted to fit between the side walls 14, 14 of the bottom bar channel and between the ribs 16, 16 of the channel and the underside of the cover 11. The anchor has a generally flat central portion 20 formed to detachably secure the lower end of a lift cord 21 of the blind and side portions 22, 22 formed to engage the lower ends of the ladder tape 24. The anchor 19 is formed to follow generally the transverse arch of the cover 11 by inclining the side portions 22, 22 downwardly slightly from the central portion 20.

The central portion 20 of the anchor 19 is provided with a so-called "keyhole slot" which is formed of a larger slot portion or hole 26 converging into a somewhat smaller slot portion or hole 27 through a necked-down transition portion 29 of a lesser width than either of the slot portions 26 or 27. The larger slot 26 may have the generally semicircular form shown in Fig. 1 and is sufficiently large to readily admit an enlargement such as the sheet metal bead 30 crimped about the lower end of the lift cord 21.

The smaller slot portion 27 is preferably generally oval in outline, the narrow dimension of the slot portion being slightly greater than the diameter of the lift cord 21 and lesser than the diameter of the bead 30. As will be explained subsequently, the length of this portion of the

slot is such that the closed end (end away from the larger slot portion 26) preferably extends beyond the side of the hole 17 in the cover 11 at all times.

The transition portion 29 of the slot 25 is preferably slightly narrower in width than the diameter of the lift cord so as to require that the cord be crowded somewhat to force it from the larger into the smaller portions of the slot 25. Preferably, the transition portion 29 of the slot is short to facilitate squeezing of the cord therethrough, and the sides of the slot converge slightly towards the smaller portion 27 of the slot to assist in entering the lift cord therein.

The marginal area 31 of the anchor about the smaller slot portion 27 is upwardly inclined away from the transition portion 29 at the open end of the slot and towards the closed end thereof. This area engages the bead 30 at the lower end of the lift cord and the inclination of the area serves to bias the lift cord and bead away from the open end of the slot portion when the lift cord is supporting the bottom bar, as in raising the blind. A cam surface 32 of the central portion of the anchor 19 serves to join the upper edge of the area 31 with the general plane of the portion. The function of this surface will be described in connection with the operation of the bottom bar assembly as a whole.

A pair of upwardly projecting tabs 34, 34 are located one on each side of the portion 29 of the slot 25. These tabs may be formed from metal displaced in forming the larger slot portion 26 and project upwardly slightly higher than the upper edge of the marginal area 31. The function of these tabs will be explained hereinafter in connection with the operation of the assembly.

The side portions 22, 22 of the anchor 19 may be provided with means for engaging the individually looped lower ends of the ladder tape branches. This ladder-tape-engaging means may comprise an opposed long finger 35 and short finger 36 struck from and extending parallel to and slightly below each side portion 22. In engaging the ladder tape branch with the fingers 35 and 36, the tape branch is first crowded onto the long finger 35 and then shifted to also extend about the short finger 36, the combined length of the fingers approximating the width of the ladder tape so as to receive the tape in flat condition. The edge 37 of each side portion 22 opposite the fingers 35 and 36 may be depressed slightly to provide additional clearance for passage of the ladder tape branch between the edges of the anchor and the inturned longitudinal edges 15, 15 of the channel 10. Similar side portions 22, 22 are shown and claimed in Nelson application S. N. 780,653.

In assembling the bottom bar organization, the looped lower ends of the ladder tapes 24 are engaged within fingers 35 and 36, a separate anchor being used for each ladder tape. The cover 11, which has previously had lift cord holes 17 formed therein, is then placed on the anchors 19 with the tabs 34, 34 of the anchors projecting upwardly through the holes. The cover may then be assembled onto the bottom bar channel 10 either by telescoping the channel onto the cover or by springing the cover into position within the channel.

After the slats of the blind have been assembled onto the ladder tapes 24 in the usual manner, the lift cords 21 may be passed downwardly through the holes in the slats. The lift cord holes in the slats and in the cover 11 are suffi-

sufficiently wide to pass the bead 30 at the bottom end of each lift cord.

To insert the lift cord end within the bottom bar, the anchor 19 is forced to the left as viewed in the drawings so as to force the tabs 34, 34 against the left side of the hole 17 in the cover, thus aligning the larger slot portion 26 with the hole in the cover (see Figs. 3 and 7). The anchor may be forced along the bottom bar by pressing with a screw driver or by hand against the tabs 34, 34 (see Fig. 2). The anchor 19 may also be moved along the bottom bar by grasping the ladder tape branches immediately above the bottom bar and pulling them in the direction in which it is desired to move the anchor.

After the bead 30 on the lift cord has been entered within the bottom bar, the anchor 19 may be moved to the right as viewed in the drawings, the lift cord 21 being guided into the transition portion 29 of the slot 25. Upon pressing the anchor 19 further to the right, the lift cord is crowded against the right margin of the lift cord hole 17 and forced into the smaller slot portion 27, which is smaller than the diameter of the bead 30 and, thus, retains the end of the lift cord. The tabs 34, 34 limit movement of the anchor 19 both to the right and to the left.

The anchor 19 is frictionally engaged between the ribs 16, 16 of the bottom bar channel and the underside of the resilient cover 11. Fortuitous movement of the anchor to release the lift cord is resisted by the raised part of the lift-cord-engaging portion of the anchor, including the area 31 and cam surface 32 which are received within the lift cord hole 17 in the cover when the anchor is moved to the right into cord-engaging position (see Figs. 4 and 6). In moving the anchor to the left, the cam surface 32 engages the margin of the lift cord hole 17 of the cover so as to force the central portion of the cover upwardly slightly against its bias (Fig. 7).

The upwardly inclined area 31 about the slot portion 27 tends to center the lift cord in the hole 17 whenever the blind is raised and the weight of the bottom bar assembly is supported by the lift cords, which further tends to prevent fortuitous disengagement of the lift cords from the bottom bar. As explained above, the smaller slot portion 27 is sufficiently long to project beyond the far or left side of the lift cord hole 17 of the cover 11 when the tabs 34, 34 are against the right-hand side of the lift cord hole (see Figs. 2, 4, and 6). Accordingly, there is no tendency for the anchor 19 to be moved to the left relative to the cover and into lift-cord-releasing position, even though the lift cord 21 be pulled sharply to the left as viewed in the drawings, since the lateral component of this pull will be resisted principally by the left side edge of the lift cord hole 17.

The above-described organization is pleasing in appearance and will safely and dependably retain the lift cords, and at the same time the lift cords may be detached quickly and without the use of special tools or disassembly of the bottom bar to permit removal of the slats for cleaning or replacement.

In the form shown of the present invention, a single anchor has been shown for both the lift cord and ladder tape, but is within the purview of the invention to use separate anchors or attaching means for the lift cord and for the ladder tape.

I claim:

1. A Venetian blind bottom bar assembly, comprising: a bottom bar channel, a cover closing the open side of the channel and provided with holes for receiving the ends of the lift cords of a blind, and a lift cord anchor located within the channel beneath each lift cord hole and displaceable lengthwise of the channel, the anchor being formed of a plate having an opening registrable with the lift cord hole for admitting the terminal enlargement of a lift cord and merging into a smaller opening to retain the lift cord registrable with the lift cord hole of the cover upon displacement of the anchor.

15 2. A Venetian blind bottom bar assembly, comprising: a bottom bar channel, a cover closing the open side of the channel and provided with holes for receiving the ends of the lift cords of a blind, and a lift cord anchor located within the channel beneath each lift cord hole and displaceable lengthwise of the channel, the anchor having an opening registrable with the lift cord hole for admitting the enlarged end of a lift cord and merging through a transition portion into a 20 smaller opening registrable with the lift cord hole of the cover upon displacement of the anchor to retain the lift cord, and having a portion adjacent the transition portion of the slot and projecting upwardly through the lift cord hole for limiting displacement movement of the anchor.

25 3. A Venetian blind bottom bar assembly, comprising: a bottom bar channel, a cover closing the open side of the channel and provided with holes for receiving the ends of the lift cords of a blind, and a lift cord anchor located within the channel beneath each lift cord hole and displaceable relative to the lift cord hole, the anchor having an opening registrable with the lift cord hole 30 for admitting the terminal enlargement of a lift cord and merging into a smaller opening registrable with the lift cord hole of the cover upon displacement of the anchor to retain the lift cord.

4. A Venetian blind bottom bar assembly, comprising: a bottom bar channel, a cover closing the open side of the channel and provided with holes for receiving the ends of the lift cords of a blind, and a lift cord anchor located within the channel beneath each lift cord hole and displaceable lengthwise of the channel, each anchor having an opening registrable with the adjacent lift cord hole for admitting the terminal enlargement of a lift cord and merging into a smaller opening registrable with the lift cord hole of the cover upon displacement of the anchor to retain the lift cord, the portion of the anchor surrounding the smaller opening being inclined upwardly away from the open end thereof to aid in biasing the cord away from the larger opening.

5. A Venetian blind bottom bar assembly, comprising: a bottom bar channel, a cover closing the open side of the channel and provided with holes for receiving the ends of the lift cords of a blind, and a lift cord anchor located within the channel beneath each lift cord hole and displaceable lengthwise of the channel, each anchor being provided with a generally flat central portion having an opening registrable with the adjacent lift cord hole for admitting the terminal enlargement of a lift cord and merging into a smaller opening to retain the lift cord registrable with the lift cord hole of the cover upon displacement of the anchor, a portion of the anchor adjacent the smaller opening being inclined upwardly from the general level of the central portion.

6. A Venetian blind bottom bar assembly, comprising: a bottom bar channel, a cover closing the opening side of the channel and provided with holes for receiving the ends of the lift cords of a blind, and a lift cord anchor located within the channel beneath each lift cord hole and displaceable lengthwise of the channel, each anchor being provided with a generally flat central portion having an opening registrable with the adjacent lift cord hole for admitting the terminal enlargement of a lift cord and merging into a smaller opening to retain the lift cord registrable with the lift cord hole of the cover upon displacement of the anchor, a portion of the anchor adjacent the smaller opening being inclined upwardly from the general level of the central portion, and the anchor being provided with a short upward projection adjacent the merging portion of the openings received by the lift cord opening to limit displacement of the anchor.

7. A Venetian blind bottom bar assembly, comprising: a bottom bar channel having upwardly and inwardly directed lateral edges and upstanding ribs projecting from the bottom between the inwardly directed edges, a resilient, transversely arched cover closing the open side of the channel and provided with holes for receiving terminal enlargements on the lift cords of a blind, and a lift cord anchor located beneath each lift cord hole and resiliently held between the upstanding ribs of the channel and the cover, the anchor being shaped to conform in general to the arched form of the cover, being displaceable lengthwise of the channel, and having an opening registrable with the lift cord hole for admitting the terminal enlargement of the lift cord and merging into a smaller opening to retain the enlargement registrable with the lift cord hole of the cover upon displacement of the anchor.

8. A bottom bar assembly as claimed in claim 7, in which each anchor is provided with a short upwardly projecting tab located at the transition portion of the slot and projecting through the lift cord hole to limit displacement of the anchor.

9. In the Venetian blind art, a lift cord anchor for a bottom bar assembly, said anchor comprising: a stamped sheet metal plate having a slot formed therein, one end portion of the slot being enlarged to admit a terminal enlargement on the end of a lift cord and the other end portion of

the slot being somewhat smaller to retain the lift cord enlargement, and a projection extending upwardly from the plate opposite the transition between the smaller and larger end portions of the slot.

10. In the Venetian blind art, a lift cord anchor for a bottom bar assembly, said anchor comprising: a stamped sheet metal plate having a slot formed therein, one end portion of the slot being enlarged to admit a terminal enlargement on the end of the lift cord and the other end portion of the slot being somewhat smaller to retain the lift cord enlargement, and a short tab formed from the metal displaced in forming the slot and projecting upwardly from the plate opposite the transition between the smaller and larger end portions of the slot.

11. A Venetian blind bottom bar assembly, comprising: a bottom bar channel, a cover closing the open side of the channel and provided with holes for receiving the ends of lift cords of the blind, a lift cord anchor located within the channel beneath each lift cord hole of the cover and displaceable lengthwise of the channel, each anchor being provided with a generally flat central portion having an opening registrable with the adjacent lift cord hole for admitting the terminal enlargement of the lift cord and merging into a smaller opening registrable with the lift cord hole of the cover upon displacement of the anchor to retain the lift cord, the anchor being provided with a short upward projection adjacent the merging portion of the openings which is received by the lift cord opening to limit displacement of the anchor, the distance from said projection to the far end of the smaller opening being greater than the width of the lift cord hole of the cover.
